ELECTRIC COUPLING CIRCUITS

Application filed January 16, 1931. Serial No. 509,116.

This invention relates to high frequency electric coupling circuits tunable over a range in frequency and adapted more especially for interconnecting successive elements of a high frequency thermionic amplifier or a radio system.

The coupling circuits of the present invention are characterized in that the voltage amplification produced thereby is caused to vary automatically with the frequency of tuning in a manner which is under the control of the designer; the design in general being preferably such as to produce a substantially constant resultant amplification, i.e. uniform sensitivity throughout the tunable frequency range.

The subject matter of the present invention has been published in a paper entitled "Theory and operation of tuned radio frequency coupling systems" by H. A. Wheeler and W. A. MacDonald. This paper was presented and distributed in printed form at the 1930 convention of the Institute of Radio Engineers held at Toronto, Canada.

With an elementary type of high frequency coupling circuit of which a two-winding transformer having a tunable secondary is a typical example, the variation in amplification with frequency is not under the control of the designer, but increases with frequency throughout the tunable range in a manner well understood, with consequent detrimental effects on the amplification, selectivity and stability of the system.

In the elementary type of coupling circuit referred to above there exists between the primary and tunable secondary circuits a coefficient of coupling which is substantially constant throughout the frequency range, a condition which is partially responsible for the mentioned increase in amplification with frequency. The present invention avoids the above noted objections by proper cooperation of different reactance elements in the primary circuit. These provide an effective coupling between input and tunable output circuits which automatically decreases with increase in the tuned frequency, and may be proportioned to offset

wholly or in part the factors operative to produce an increase in amplification with frequency.

Coupling circuits operative to attain substantially the same objectives as the present invention but differing therefrom as regards both the methods of such attainment and in the circuit arrangements utilized, are disclosed in Patent No. 1,763,380 issued June 10, 1930 to C. E. Trube and in his copending applications Serial No. 101,906 filed April 14, 1926 and Serial No. 120,045 filed July 2, 1926.

The Trube circuits are characterized in the provision of a tunable secondary circuit having a primary circuit coupled thereto at least a portion of which is resonant below the tunable range for providing a coupling component between primary and secondary circuits which decreases with increase in the tuned frequency. This variable coupling component supplemented by a fixed coupling provides a resultant coupling which automatically falls off at a pre-selected rate as the tuned frequency is increased.

With the circuits of the present invention on the other hand, a tunable secondary circuit is coupled to a primary circuit at least a portion of which is resonant above the tunable frequency range for providing a coupling component between primary and secondary circuits which increases with the tuned frequency. This coupling component increasing with frequency is subtracted from a fixed component to provide a resultant coupling which, as in the case of the Trube circuits, automatically falls off at a preselected rate with increase in the tuned frequency.

In certain embodiments of the present invention the primary circuit is coupled both inductively and capacitively to the tunable secondary circuit, with the capacitive coupling arranged to oppose the magnetic coupling. The capacitive coupling which of necessity increases with frequency is thus subtracted from the substantially invariable magnetic coupling to provide the mentioned resultant coupling which varies in the inverse order of the tuned frequency.

With certain other embodiments of the present invention the magnetic coupling between primary and secondary circuits is absent; in fact there are no clearly defined primary and secondary circuits, but rather a tunable network containing reactive elements interposed between input and output terminals. For circuits of this type, the resultant coupling between input and output terminals is determined by the ratio of two reactive elements the impedances of which vary with frequency at such different rates as to provide the desired automatic variation in coupling between input and output terminals.

Referring now to the drawings:

Figs. 1, 2 and 3 show elementary coupling circuits in accordance with the present invention wherein a primary circuit is coupled in opposed capacitive and inductive relation to a tunable secondary circuit;

Figs. 4 and 5 show modifications of the invention wherein the magnetic coupling is absent, the coupling circuits being more in the nature of tunable networks interposed between input and output terminals;

Fig. 6 shows the circuit of Fig. 3 in association with an antenna system connected to the input terminals thereof; while

Figs. 7 and 8 disclose the manner of connecting the anode circuit of a thermionic element to the input terminals of the circuits of Figs. 3 and 4 respectively.

The circuit of Fig. 1 includes a secondary coil L and a variable tuning condenser C bridged between output terminals O, the lower output terminal being conductively joined to the lower of a pair of input terminals I in order to provide a common or ground connection. Inductively related to the secondary coil L is a primary coil L₂ so connected between input terminals I that the upper input and output terminals are of like alternating current polarity. A coupling condenser C₁ of small capacity is connected between the ungrounded terminals of coils L₂ and L for providing a capacitive coupling between primary and secondary circuits which opposes throughout the tunable frequency range the magnetic coupling therebetween due to the mutual inductance M. An additional capacity C₂ may be connected between the input terminals I, or, as is more generally the case, a capacity C₂ may exist between the input terminals in the operation of the coupling circuit due to the type of input circuit connected thereto.

In order, with the circuit connections specified, to assure that the capacitive coupling between primary and secondary circuits due to the condenser C₁ will substantially oppose the magnetic coupling therebetween due to the mutual inductance M, throughout the tunable frequency range, it is necessary that the inductance of the primary

coil L₂ together with the associated capacities, including that of the coupling condenser C₁ and any capacity C₂ effectively bridged between the input terminals, be resonant at a frequency above the tunable range as determined by adjustment of condenser C. For most efficient operation, especially where an approach toward uniform sensitivity throughout the tunable range is desired, the resonance frequency of the primary circuit as determined by elements L₂, C₁ and C₂, should be only slightly higher than the highest frequency within the tunable range.

It will be apparent from the above considerations that whereas the magnetic coupling between primary and secondary circuits is substantially independent of the tuning adjustment, the opposed capacitive coupling of necessity increases with the tuned frequency as a result of the inverse variation with frequency in the impedance of the coupling condenser C₁. The combination of these two factors produces a resultant or effective coupling between input and output terminals which automatically decreases with increase in the tuned frequency at a rate which is dependent upon the relative proportioning of the reactive elements.

The coupling circuit of Fig. 1 has been described in some detail as being generic to the type of coupling circuit disclosed herein. The specific circuit of Fig. 1 however, constitutes no part of the present invention, having been heretofore broadly disclosed and claimed in a copending application of Wm. A. MacDonald Serial No. 469,040, filed July 19, 1930, now U. S. Patent 1,888,278, issued November 22, 1932; specific modifications thereof being disclosed and claimed in an application of H. A. Wheeler Serial No. 480,947 filed Sept. 10, 1930.

The modification of Fig. 2 differs from that of Fig. 1 by the addition of the inductance L₃ connected in series with the primary coil L₂ between input terminals I. Coil L₃ is uncoupled magnetically with respect to coils L and L₂ as is indicated by drawing the coil with its axis at right angles to the axes of coils L and L₂.

Primary coil L₂ is resonant with its associated capacities at a frequency considerably higher than the tuning range. Coil L₃ is added to reduce the primary resonant frequency to a value nearer to but still above the tuning range. In this way the effective opposing capacitive coupling can be controlled by the value of L₃, without varying the inductive coupling M.

In the modification of Fig. 3 the condenser C₁ instead of being connected to the upper terminal of the secondary coil L as in Fig. 1, is tapped to an intermediate point thereof. This change is in the direction of

increasing the flexibility of the system since it provides a means for varying the capacitive coupling between primary and secondary circuits without changing the value of C_1 or appreciably affecting the resonance frequency of the primary circuit.

With the circuits of Figs. 1 to 3 inclusive, the total inductance in the primary circuit should be of the same order of magnitude 10 as the inductance of the secondary coil L_2 . A moderate degree of coupling, of the order of 30 percent, should be employed between primary and secondary circuits. If the coupling is too close the circuits will be tuned 15 as a unit thus preventing the resonance frequency of the primary circuit from having the desired effect in controlling the amplification characteristics of the circuit. A degree of coupling which is too loose is of 20 course undesirable since there results a loss in sensitivity.

In the modification of Fig. 4 the magnetic coupling between primary and secondary coils L_2 and L is omitted, there being 25 present only the capacitive coupling due to condenser C_1 . In this instance a condenser C_2 is connected in series with coil L_2 between input terminals I. Condenser C_2 and primary coil L_2 should be resonant 30 at the mentioned frequency above the tunable range determined by adjustment of C .

It will be noted that in the modification of Fig. 4 two paths are provided in parallel between input terminals I. One of these 35 paths contains element L_2 and C_2 , while the other path contains the coupling condenser C_1 and the tuned circuit LC . Due to the presence of condensers C_1 and C_2 , the impedances of both paths are caused to decrease with increase in the tuned frequency, but at such different rates that as the frequency of tuning increases, an increasing percentage of the total current flowing past the input terminals I will be shunted 40 through the primary circuit path containing elements L_2C_2 leaving a decreasing portion flowing through the tuned circuit LC . Thus the effective coupling between primary and secondary circuits automatically 45 falls off as the frequency of tuning increases.

The circuit of Fig. 5 operates on somewhat the same principle. In this modification L_2 is tuned by C_2 to a frequency above 50 the tunable range; likewise L_2 is tuned by C_1 to a frequency above the range. The resonance frequency of L_2C_2 is, however, further removed from the tuning range than that of L_2C_1 , so that as the circuit is tuned 55 to higher frequencies by adjustment of C , the impedance of L_2C_2 bridged between the input terminals will increase at a rate less rapid than that of L_2C_1 , with the result that an increasing portion of the total current flowing past the input terminals I will be

shunted through the impedance L_2C_2 . In this way the effective coupling between input and output terminals may be caused to decrease in a preselected manner with increase in the tuned frequency.

70

Fig. 6 merely shows the modification of Fig. 3 with an antenna circuit A connected to the input terminals thereof. The antenna-to-ground capacity of the antenna circuit constitutes the capacity C_2 . The connection between the lower input and output terminals is not shown since a conductive path through the ground connections is provided therebetween.

75

In Fig. 7 the anode circuit of a thermionic tube V is connected to the input terminals of the Fig. 3 circuit. The upper input terminal is joined directly to the anode, while the lower input terminal is connected to the +B lead extending to a space current supply source for supplying energy to the space current path, including the primary coil L_2 and the grid-biasing resistor R joined to the cathode. Condensers D serve to by-pass the high frequency current. The direct connection between the lower input and output terminals is omitted to prevent grounding the +B lead at the rotor element of condenser C. Condenser C serves as a blocking as well as a coupling condenser. In Fig. 7 the capacity C_2 of the coupling circuit is provided by the anode-to-ground tube capacity.

80

In Fig. 8 the anode circuit of a thermionic tube V is connected to the input terminals of the circuit of Fig. 4. In this instance it is necessary to employ a choke coil L_4 in order to complete the space current supply path owing to the presence of C_2 95 in series with L_2 in the coupling circuit.

100

The coupling circuits of the present invention are such that the rotor element of the tuning condenser may in each instance be grounded, this being desirable to prevent 105 undesired coupling effects.

110

Each of the circuits of Figs. 1 to 5 inclusive may be associated with an antenna system after the fashion shown in Fig. 6. The modifications of Figs. 1 to 3 will operate successfully when connected to a thermionic tube in the manner shown in Fig. 7; whereas a choke coil arrangement is required for the circuits of Figs. 4 and 5.

115

It is frequently convenient and advantageous to employ inherent capacity in place of a physical condenser for C_1 or C_2 in these circuits. This is particularly recommended in the case of C_1 in Figs. 1 to 8 inclusive and in the case of C_2 in Figs. 1, 2, 3, 5 and 7.

120

What is claimed is:

1. A high frequency electric coupling circuit tunable over a range in frequency comprising a variable tuning condenser connected between an output and a common terminal, an inductance connected between an

125

130

input and said common terminal, and a fixed capacity shunted by a second inductance connected between said input and output terminals, said second inductance together with said fixed capacity being resonant at a frequency slightly above said tuning range.

2. A high frequency electric coupling circuit tunable over a range in frequency comprising a variable tuning condenser connected between an output and a common terminal, a first inductance shunted by a fixed capacity connected between an input and said common terminal, and a second inductance shunted by a fixed capacity connected between said input and output terminals, said second inductance together with its associated fixed capacity being resonant at a frequency slightly above said tuning range, and said first inductance together with its associated capacity being resonant at a still higher frequency.

In testimony whereof I affix my signature.

HAROLD A. WHEELER.
